UNITED STATES PATENT OFFICE.

MONTGOMERY J. ZAHNISER, OF WASHINGTON, PENNSYLVANIA.

OIL-CUP.

SPECIFICATION forming part of Letters Patent No. 662,051, dated November 20, 1900.

Application filed April 9, 1900. Serial No. 12,136. (No model.)

To all whom it may concern:

Be it known that I, MONTGOMERY J. ZAHNISER, a citizen of the United States, residing at Washington, in the county of Washington 5 and State of Pennsylvania, have invented certain new and useful Improvements in Oil-Cups; and I do hereby declare the following to be a full, clear, and exact description of the invention, which will enable others skilled 10 in the art to which it appertains to make and use the same.

My invention relates to improvements in oil-cups or lubricators for machinery.

The invention relates more particularly to 15 the cover and to means for securing the same in place and to prevent its becoming loosened or disengaged on account of the vibrations to which it may be subjected.

Generally speaking, the invention consists 20 of the usual oil or grease cup, cylindrical in shape, with an open top and a screw-threaded hollow stem for attachment to the machinery to be lubricated. The cap or cover is disk-shaped, of slightly greater diameter than the 25 cup, and is attached thereto by a screw-threaded depending portion engaging with threads formed upon the inside of the cup. When in place and fully screwed down, a portion 30 of the cover will project beyond the sides of the cup. This portion gives a purchase in adjusting the cup and serves as a place of engagement for the locking-piece. The locking-piece is cam-shaped, pivoted to a fixed pin from the side of the cup, and engages with 35 the lower projecting face of the cover. A spring keeps the cam in engagement with the cover. The cam is so proportioned and arranged as to afford no resistance to the application of the cover, but will engage and 40 firmly lock it upon any attempt at removal being made. To allow the cover to be removed, a depending finger-piece is provided, by means of which the cam may be disengaged. Stops are provided to limit the extent of movement of the cam.

In order to better understand the nature of the invention, attention is to be directed to the accompanying drawings, in which—

Figure 1 is a top view of the oil-cup with 50 the cover removed. Fig. 2 is a bottom view of the cover. Fig. 3 is a sectional view of

the cup and cover, and Fig. 4 is a side view of the complete cup.

In all the several views like parts are designated by identical letters of reference.

55

The cup is formed of a cylindrical body portion A, with a hollow screw-threaded stem B for attachment to the machinery. The disk-shaped cover D is provided with a screw-threaded depending flange D', which engages 60 with corresponding threads cut in the upper portion of the inner face of the cup. A portion D² of the cover overhangs the locking-lever. This portion may be milled to allow more facile adjustment. A portion of one of 65 the sides of the cup is cut away at C for the attachment of the locking-piece a and to prevent the locking-piece projecting far beyond the plane of the outside of the cup. This latter is eccentrically pivoted upon the bolt 70 g, secured by screw-threads within the side of the cup. A cam portion a' of the locking-piece engages with the overhanging part D² of the cover and allows the latter to be turned in the direction of the arrow, Fig. 4, but not 75 the other way unless released. A depending portion provided with a finger-piece a² is provided, by means of which the locking-piece may be disengaged from the cover. To assist the gripping action of the locking-piece, 80 a spring b is provided, concentrically surrounding the bolt g and engaging with the locking-piece and the cup.

e e' are stops to limit the movement of the locking-piece.

85

g' is a lock-nut for the bolt g.

The cover is attached by engaging the screw-threaded part D' with the cup and turning it in the direction of the arrow until closely in engagement with the cup, the locking-piece 90 a imposing no resistance. This piece by its eccentric action will effectually prevent the cover being removed by vibration or accident. To remove the cover, the finger-piece a² must first be depressed and retained in such depressed position until the cover is removed.

Having now described and ascertained the nature of my invention, what I claim, and desire to secure by Letters Patent, is—

1. In an oil-cup the screw-threaded body A 100 thereof, a cam-lever a pivoted thereon, the cover D, screw-threads thereon, the over-

hanging portion D^2 , engaging with the cam-lever, substantially as described.

2. In an oil-cup the screw-threaded body A thereof, a cam-lever a pivoted thereon, the cover D, screw-threads thereon, the overhanging portion D^2 , engaging with the cam-lever and a spring b for engaging the lever, substantially as described.

3. In an oil-cup the screw-threaded body A thereof, a cam-lever a pivoted thereon, the cover D, screw-threads thereon, the overhanging portion D^2 , engaging with the cam-lever, a spring b for engaging the lever and a finger-piece a^2 for releasing the lever, substantially as described.

4. In an oil-cup the internally-screw-threaded body A thereof, a cam-lever a pivoted thereon, the cover D, the depending screw-threaded flange D' , thereon, the overhanging portion D^2 , engaging with the cam-lever, substantially as described.

5. In an oil-cup, the internally-threaded

body A, the cut-away portion C, the bolt g thereon, the cam-lever a , supported thereby, the cover D, the depending screw-threaded flange D' thereon, the portion D^2 , overhanging said cut-away portion, and engaging with the cam-lever, substantially as described.

6. In an oil-cup, the internally-threaded body A, the cut-away portion C, the bolt g thereon, the cam-lever a , supported thereby, the cover D, the depending screw-threaded flange D' thereon, the portion D^2 , overhanging said cut-away portion, and engaging with the cam-lever, and the spring b , surrounding the bolt g , and connecting the cam-lever and the body, substantially as described.

This specification signed and witnessed this 7th day of April, 1900.

MONTGOMERY J. ZAHNISER.
